DESIGN FOR AN ELECTRICAL HUMIDIFY- ING DEVICE

Elmer A. Reid, Morrisville, Pa.

Application October 8, 1937, Serial No. 72,083

Term of patent 7 years

To all whom it may concern:

Be it known that I, Elmer A. Reid, a citizen of Great Britain, residing at Morrisville, in the county of Bucks and State of Pennsylvania, have invented a new, original, and ornamental Design for an Electrical Humidifying Device, of which the following is a specification, reference being had to the accompanying drawings, forming part thereof.

Figure 1 is a side elevational view of an electrical humidifying device showing a liquid supply

receptacle, an evaporating receptacle and a tray-like base. The other side of the device is substantially like the side shown.

Figure 2 is a top view of the electrical humidifying device.

I claim:

The ornamental design for an electrical humidifying device, substantially as shown and described.

ELMER A. REID.
